By attorney

UNITED STATES PATENT OFFICE.

CHARLES L. HENDRICKS, OF SAN MATEO, CALIFORNIA.

COMBINED BOOK PROTECTOR AND MARKER.

Application filed August 5, 1927. Serial No. 210,923.

This invention relates to a combined book protector and marker, and has particular reference to means for protecting the cover of a book and at the same time marking the 5 pages thereof.

The primary object of the invention is to provide a device of the character described which is adjustable to books of varying widths and is equipped with means insertable between the pages of the book so that the reader can positively identify the last page read.

An additional object of this invention is to provide a combined book protector and 15 marker that is economical to manufacture, ornamental in appearance, positive in operation and highly serviceable in use.

Other objects and advantages will be apparent during the course of the following 20 description.

In the accompanying drawing forming a part of this specification and in which like numerals are employed to designate like parts throughout the same,

25 Figure 1 is a perspective view of the device per se,

Figure 2 is an edge elevation of a book and its protecting cover, showing the device applied to the cover and the indicating means 30 inserted between the pages of the book, and

Figure 3 is a side elevation of a book without a paper cover showing the device applied to the book.

It oftentimes happens that in the reading 35 of a book the page that was last read cannot be identified. Furthermore the practice has been often resorted to of folding over or "dog-earing" the edge of the page for the purpose of identifying the last reading point.

40 This folding over of the edge of the page tends to mutilate the book. In addition to this fact, it often occurs that the cleanliness of the book cover is desired to be preserved. It is not always possible, unless the paper

45 cover is kept intact thereon.

I have therefore devised an article which will positively assure the retention of the paper cover of the book, and at the same time have combined with the device a marking element in the form of a tape which when inserted between the pages of the book, will positively identify the page when the

reading of that section of the book was discontinued.

In the accompanying drawings wherein 55 for the purpose of illustration is shown a preferred embodiment of my invention, the numeral 4 designates a book having the usual back 5 and a paper cover 6. To the book there is secured my device which embodies in its construction a clip 7 having its extremity 8 bent as at 9 so as to provide means for securing the clip to one section of the book cover 6.

To the clip 7 there is secured one end of a 65 tape 11, which extends around the back and terminates in a marking element 12 adapted to be inserted between the pages 13 of the book.

This tape carries thereon a second clip 14 70 of similar formation to the clip 17 with the exception that the clip 14 is provided with apertures 15 and 16 therein, through which a portion of the tape is trained. This construction permits the clip 14 to be slidably 75 positioned on the tape so that the device is readily applicable to books of varying widths.

In the application of the device the clip 7 is first secured to one side of the book the 80 down-turned portion 8 serving to positively secure the clip thereon. The tape is then secured about the book until it assumes the position illustrated to advantage in Figures 2 and 3, the use of the device depending upon 85 whether the book with a paper cover is utilized, or a book without the paper cover.

After the tape has been so positioned the clip 14 is adjusted on the opposite portion of the cover and the marking portion 12 90 readily inserted where desired between the pages of the book to be marked.

From the foregoing description considered in connection with the accompanying drawing, it will be apparent that I have provided 95 a simply constructed device which will readily accomplish the objects set forth and because of its ornamental appearance will in no wise detract from the appearance of the book.

It is to be understood that the form of my invention herewith shown and described is to be taken as a preferred example of the same, and that various changes relative to

the shape, size, material and arrangement of parts may be resorted to without departing from the spirit of the invention, or the scope of the subjoined claim.

Having thus described my invention, I claim:—

A combined book protector and marker

comprising a tape element, a clip secured to one end of said tape element, a second clip slidably mounted on said tape element, and page marking means carried by said element.

In testimony whereof I affix my signature.

CHARLES L. HENDRICKS.
